DESIGN FOR A RAZOR BLADE SHARPENER

Albert F. Weiss, University City, Mo.

Application March 30, 1935, Serial No. 56,131

Term of patent 14 years

To all whom it may concern:

Be it known that I, Albert F. Weiss, a citizen of the United States, residing at University City, county of St. Louis, State of Missouri, have invented a new, original, and ornamental Design for a Razor Blade Sharpener, of which the following is a specification, reference being had to the accompanying drawing, forming part thereof.

Fig. 1 is a top plan view of a razor blade sharpener showing my new design.

Fig. 2 is a side elevation thereof, the opposite side being the same.

Fig. 3 is another side elevation, the opposite side being the same.

Fig. 4 is a perspective view of the razor blade sharpener looking toward the bottom end.

I claim:

The ornamental design for a razor blade sharpener, as shown and described.

A. F. WEISS.
